UNITED STATES PATENT OFFICE.

NACE EDWARDS, OF BARTON, OHIO.

CAR-CO尤LING.

SPECIFICATION forming part of Letters Patent No. 367,798, dated August 9, 1887.

Application filed April 7, 1887. Serial No. 234,050. (No model.)

To all whom it may concern:

Be it known that I, NACE EDWARDS, a citizen of the United States, residing at Barton, in the county of Belmont and State of Ohio, have invented a new and useful Improvement 5 in Car-Couplings, of which the following is a specification.

My invention relates to improvements in automatic car-couplings; and it consists in 10 certain novel features hereinafter described, and then pointed out in the claims.

In the accompanying drawings, Figure 1 is a side elevation of the coupling and its immediate connections. Fig. 2 is an end view, and 15 Fig. 3 is a bottom plan view, of the upper half of the draw-head. Fig. 4 is a horizontal section, showing two couplings together. Fig. 5 is a vertical transverse section of the coupling.

Referring to the said drawings by letter, A 20 designates the body of a stock-car of the usual construction, and B the draw-head secured to the bottom thereof, at the end of the same. To the front end of the draw-head, on the under side of the same, I secure a fender, 25 C, which projects forward a suitable distance from the draw-head, as shown. This fender consists of a bar of any suitable material, preferably metal, having its sides converging to a sharp edge at its front end. It is secured 30 to the draw-head midway the sides thereof, and is adapted to engage against a similar fender on the coupled draw-head, and thereby turn the link into position to be engaged by the coupling-pin, as will hereinafter more fully appear. The rear end of the draw-head is 35 inserted through and supported by a cross-bar, D, on the bottom of the car, and its extremity is provided with a circumferential flange, d, which engages against the rear side of this 40 cross-bar, and thereby prevents the draw-head being drawn entirely from under the car.

E E are a pair of coiled springs, which have 45 their opposite ends secured to the cross-bar D and the upper and lower sides of the draw-head, as clearly shown in Fig. 1. These springs serve to press the draw-head forward and allow it to yield to the blow given by an approaching draw-head in the operation of coupling.

The draw-head is formed in two equal parts, 50 F F', the upper part, F, having the mechanism for supporting the pin, and the lower part, F',

being provided with the grooves f, to receive the coupling-link. The front end of each part of the draw-head is provided with a central 55 vertical ridge or projection, g, which forms two mouths, g', and the coupling-link G is secured within the draw-head, just in rear of this ridge g, and projects therefrom. The draw-head is provided with two pin-holes, one 60 in rear of each mouth g', and a coupling-pin, H, is inserted in each pin-hole. These coupling-pins are simultaneously withdrawn from the draw-head by means of an angle-lever, I, pivoted to the end of the car, and having one 65 arm connected to the coupling-pins by a chain or rope, i, and its other end projecting through a keeper, J. A coiled spring, j, is arranged in rear of the angle-lever I and bears against the same to hold it normally in a lowered position, whereby the pins will not be unduly 70 lifted.

The lower ends of the coupling-pins are provided with the annular grooves n, which are engaged by the spring K, secured to the 75 under side of the upper half of the draw-head when elevated, and thereby held against entire withdrawal from the draw-head and against premature dropping. The spring K consists of a central portion, k, coiled around a stud on the 80 under side of the upper part of the draw-head, and the arms k' extending therefrom in opposite directions, and provided at their ends with the loops k'. The arms k' engage the grooves in the coupling-pins, and are released 85 therefrom by means of a rock-shaft, L, actuated by the coupling-link. This rock-shaft L is journaled in the under side of the upper part of the draw-head, and has the arms l l' at its opposite ends, the arm l being in the 90 path of the coupling-link and the arm l' being at right angles to the arm l, and adapted to engage the loop k' of the spring K.

The operation of my device is simple, and will be readily understood. When the draw-heads are made to approach each other, the fenders C will engage and the draw-heads will be thrown slightly to one side in opposite directions, and the link of each draw-head will enter the opposite draw-head, and, striking against the arm l of the rock-shaft L, will 95 rotate the said shaft. The rotation of the shaft causes the arm l' to engage the loop k' of the spring K and draw the said spring 100

backward out of engagement with the annular groove in the coupling-pin, which consequently falls through the link, and the coupling is completed. To uncouple the cars, it is necessary only to lift the pins by means of the angle-lever I, as will be readily understood.

Having thus described my invention, what I claim, and desire to secure by Letters Patent, is—

1. The combination, with the coupling devices, of the angle-lever I, pivoted to the end of the car and connected to said coupling devices, and the spring j, secured to the end of the car and bearing on the angle-lever, substantially as set forth.

2. The combination, with the draw-head, of the spring K, secured therein, and having the arms k' arranged in the paths of the coupling-

pins and provided with the loops k², and the rock-shafts L, secured within the draw-head 20 and having the arm l' engaging the loop k² and the arm l in the path of the coupling-link, substantially as specified.

3. The combination, with the draw-head, of the spring K, supporting the coupling-pin, and the rock-shaft L, actuated by the coupling-link to release the spring K from the pin, substantially as set forth.

In testimony that I claim the foregoing as my own I have hereto affixed my signature in presence of two witnesses.

NACE EDWARDS.
